CLOSURE DEVICE FOR A TUBULAR MEMBER ADAPTED FOR DISPLAYING ADVERTISING MATTER

John C. Dunn, Providence, R. I.

Application November 21, 1938, Serial No. 241,576

7 Claims. (Cl. 40—20)

My invention relates to closure devices for tubular members.

While my invention may be employed as a closure device for a tubular member of any type, such as a can, container, pipe end, etc., it is particularly adapted for use in displaying advertising matter on the end of a tubular spool member.

My invention includes a cover for the tubular member and expanding wedge means having portions eccentrically pivotally secured together mounted on the inner surface of said cover, insertable when in alignment within said tubular member end and pivotable on relative rotation of said cover and spool member by the action of 10 portions of said expanding wedge means frictionally contacting the inner periphery of said tubular member to positions positively gripping the inner wall of said tubular member to retain said cover to said tubular member end.

20 I believe I am the first therefore, to provide a cover and expanding wedge means having portions thereof adapted to be inserted within the tubular member end when in alignment, adapted on rotation thereof, to frictionally contact the inner wall of said tubular member to cause said wedge means to expand to positively grip the inner wall of said tubular member to secure said closure device to said tubular member end, namely, a device which functions on the frictional 25 engagement of the portions thereof with the inner wall of said tubular member to cause positive locking of the cover member thereto. The cover member, may if desired, carry suitable advertising 30 insignia either directly imprinted thereon, or on 35 a label pasted, or otherwise secured thereto.

A further object of my invention is to provide a securing means which will function on slight variations in diameter of the tubular member itself.

These and such other objects of my invention 40 as may hereinafter appear will be best understood from a description of the accompanying drawing which illustrates my closure device applied as a device for displaying advertising matter on the end of a tubular spool member.

45 Fig. 1 is a perspective view of an embodiment of my invention adapted to carry advertising matter applied as a closure device for the end of a tubular spool member.

50 Fig. 2 is a vertical sectional view taken along the line 2—2 of Fig. 1 with the locking disc members of my invention in alignment.

55 Fig. 3 is a vertical sectional view similar to Fig. 2 with the disc members rotated to relative locking position.

Fig. 4 is a longitudinal section view taken along the line 4—4 of Fig. 2.

Fig. 5 is a longitudinal sectional view taken along the line 5—5 of Fig. 3.

60 Fig. 6 is an inner end elevation of my improved

end closure device per se with the discs thereof in alignment.

Fig. 7 is an inner end elevation of my improved end closure device per se with the discs thereof relatively rotated to disaligned locking position. 5

In the drawing, wherein like characters of reference indicate like parts throughout, 10 generally indicates an end closure device for a tubular member constructed in accordance with my invention. 10

While as stated, my improved end closure device may be employed as a closure device for a tubular member such as a can or tubular paper container, it is particularly adapted for use in displaying advertising matter on the end of a tubular spool 12 of a type adapted to have various 15 types of textile fabric or threads wound thereon.

My invention includes a cover 14 for the end of the tubular or spool member 12. While this may be of any particular shape, in the embodiment shown, it has an external periphery substantially the size of the external periphery of the spool 12. Said cover 14 may carry advertising matter 16 on the outer surface thereof and it is immaterial whether the advertising matter 16 be 20 directly imprinted on the cover or on a label 18 adapted to be affixed to the outer surface of said cover. 25

I provide expanding wedge means having portions eccentrically pivotally secured together and 30 mounted on the inner surface of said cover insertable when in alignment within said spool member and pivotable on relative rotation of said cover and spool member on peripheral contact 35 thereof with the inner wall of said spool or tubular member to disaligned positions gripping the inner wall of said spool member to secure said cover to said tubular member end.

40 In my preferred embodiment, said wedge means includes an outer disc member 20 of substantially the internal periphery of said tubular spool member 12 permanently secured to the inner surface of said cover 14 in any suitable manner such as by glue 22, an inner disc member 24 of substantially the internal periphery of said tubular spool 45 member and means 26 to eccentrically secure said inner disc member 24 on said outer disc member 20. Said mounting means 26 may consist of any suitable shape, such as a pin or other device projecting axially through said inner disc member 24 and axially within said outer disc member eccentrically of said disaligned disc members. In the preferred embodiment shown, as said eccentric mounting means 26, I provide a rivet 26 50 having a head 28 adapted to abut the inner surface of the inner disc and prong means 30 inserted through said inner disc 24, outer disc 20 and reversely embedded within the wall of said cover 14. It is obvious, however, that any suit- 55

able type of eccentric mounting means 26 may be employed.

I preferably construct the inner periphery of the tubular member 12 and the outer peripheries 32 and 34 of the outer and inner disc members 20 and 24 of materials capable of having frictional contact and braking action on each other. While any suitable type of material may be employed, I have found rough card board surfaces ideal for this purpose and hence preferably construct the spool member 12 and the discs 20 and 24 of card board, although it is obvious that any other suitable type of materials which will cause frictional gripping action with each other may be employed.

15 As shown in Fig. 6 the disc members 24 and 20 are aligned for insertion within said tubular member and after insertion, on rotation of said cover 14, said discs 20 and 24 are relatively eccentrically rotated by frictional contact of the 20 peripheries thereof with the inner periphery of said tubular spool member and thus, with each portion thereof in contact tending to remain stationary and being eccentrically pivoted outwardly by rotation of said cover, said contacting portions 25 relatively expand to grip opposite portions of the inner periphery of the tubular spool member positively to secure said closure device to said tubular spool member end in use.

I have found that with most substances a suitable frictional clamping action may be obtained even if metal be employed as one or more of the contacting surfaces, such as in a can. I may also, by merely attaching two of my improved closure devices together, provide means or a union for 35 joining pipe ends together, such as in making up a fence.

It is obvious that the end closure device may be readily removed from its tubular member by rotating the device in the opposite direction to 40 again bring the discs into alignment so that they may be axially withdrawn from the end of the tubular member.

It is apparent that I have provided a novel type of end closure device for a tubular member with 45 the advantages described above.

It is understood that my invention is not limited to the specific embodiment shown and that various deviations may be made therefrom without departing from the spirit and scope of the 50 appended claims.

What I claim is:

1. An end closure device for displaying advertising matter on the end of a tubular spool member, comprising a cover for the tubular spool member end carrying said advertising matter, an outer disc member of substantially the internal periphery of said tubular spool member permanently secured to the inner surface of said cover, an inner disc member also of substantially the 55 internal periphery of said tubular spool member and means to eccentrically mount said inner disc member on said outer disc member, whereby said disc members may be aligned for insertion within said tubular spool member end and on rotation of said cover said discs may be relatively eccentrically rotated by frictional contact of the periphery thereof with the inner periphery of said tubular spool member to relatively expand to grip opposite portions of the inner periphery 60 of the tubular spool member to secure said closure device to said tubular spool member end.

2. A closure device for a tubular member, comprising a cover for the member end, an outer disc member of substantially the internal periphery of said tubular member permanently secured to the inner surface of said cover, an inner disc member also of substantially the internal periphery of said tubular member and means to eccentrically mount said inner disc member on said outer disc member, whereby said disc members may be aligned for insertion within said tubular member end and on rotation of said cover said discs may be relatively eccentrically rotated by frictional contact with the inner periphery of said tubular member to relatively expand to grip opposite portions of the inner periphery of the 10 tubular member to secure said closure device to said tubular member end.

3. An end closure device for displaying advertising matter on the end of a tubular spool member, comprising a cover for the spool member end carrying said advertising matter, an outer disc member of substantially the internal periphery of said spool member permanently secured to the inner surface of said cover, an inner disc member also of substantially the internal periphery of said spool member and means to eccentrically mount 15 said inner disc member on said outer disc member.

4. A closure device for a tubular member, comprising a cover for the tubular member end, an outer disc member of substantially the internal periphery of said tubular member permanently secured to said cover, an inner disc member also of substantially the internal periphery of said tubular member and means to eccentrically 20 mount said inner disc member on said outer disc member.

5. A closure device for a tubular member, comprising a cover for the tubular member end, an outer disc member of substantially the internal periphery of said tubular member permanently secured to the inner surface of said cover, an inner disc member also of substantially the internal periphery of said tubular member and pin means projecting axially outwardly through said 25 inner disc member and axially within said outer disc member eccentrically of said disc members when in alignment.

6. An end closure device for displaying advertising matter on the end of a spool member, comprising a cover for the spool member end carrying said advertising matter and expanding wedge means having portions eccentrically pivotally secured together mounted on the inner surface of said cover insertable when in alignment within said spool member end, and pivotable on relative rotation of said cover and spool member to positions gripping the inner wall of said spool member to secure said closure device to said tubular member end.

7. A closure device for a tubular member, comprising a cover for the tubular member end and expanding wedge means having portions eccentrically pivotally secured together mounted on the inner surface of said cover insertable when in alignment within said tubular member end, and pivotable on relation rotation of said cover and tubular member to positions gripping the inner wall of said tubular member to secure said closure device to said tubular member end.

JOHN C. DUNN.
